UNITED STATES PATENT OFFICE.

GEORGE W. VINSON, OF MAYFIELD, KENTUCKY.

CLEVIS.

SPECIFICATION forming part of Letters Patent No. 366,140, dated July 5, 1887.

Application filed May 4, 1887. Serial No. 237,148. (No model.)

To all whom it may concern:

Be it known that I, GEORGE W. VINSON, of Mayfield, in the county of Graves and State of Kentucky, have invented a new and useful 5 Improvement in Clevises, of which the following is a specification.

My invention is an improved clevis; and it consists in certain constructions and combinations of parts, as will be hereinafter described, and pointed out in the claims.

In the drawings, Figure 1 is a side elevation of my invention as in use, the beam being shown in section. Fig. 2 is a perspective view of the clevis detached from the beam, and 15 Fig. 3 is a detail section illustrating the draft-hook and the front clevis-bar.

The clevis comprises two sections, A and B, the former of which, for convenience of reference, I term the "main" section, while the 20 other section may be termed the "supplemental" plate or section. The main section A comprises the side plate, C, and the front bar, D, formed a part of and arranged at right angles to the side plate, C, the free end or extremity of said front bar, D, being threaded at 25 1, as shown. The side plate, C, has near its rear end a threaded opening, 2, for the wrench-bolt E, and is provided in advance of said opening 2 with an opening, 3, for the fastening 30 bolt or pin F. The sections A B, it will be seen, are connected at their forward ends by the arm D of the plate C screwing into the supplemental section, and at their rear ends by the bolt E. By this construction, it will be 35 seen, the clevis may be quickly adjusted to beams of different thicknesses; and this, too, is attained without necessitating the bending of plates B C toward or from each other, and without necessitating the front bar being 40 formed separate from both the said plates B C. Thus I form the clevis-frame B C D in but two pieces, simplifying the construction and reducing the liability of losing any of the parts. The top plate has at its rear end an opening, 45 4, for the wrench-bolt, a hole, 5, between its ends for the fastening-bolt F, and a threaded opening, 6, is provided near its forward end for the end of the front bar or arm, D. The arm D is formed non-circular in cross-section, 50 having an eccentric portion or wing, d, extended preferably to the rear, as shown. In

such eccentric wing I form notches d', the arm on a cross-section drawn through said notches being approximately circular, as shown. The draft-hook G has an opening, g, formed with 55 an extension or wing, g', corresponding to the eccentric wing of the arm D. When the hook is turned with its opening g in full register with the arm D and the wings thereof, as shown in dotted lines, Fig. 3, it may be adjusted 60 along said arm to bring the draft-hook at any suitable height to regulate the depth of the plow. When at the proper height, the draft-hook may be turned forward to the position shown in full lines, Fig. 3, when the team may 65 be hitched. It will be seen that to effect an adjustment of the draft-hook up or down it is only necessary to remove the bolt F and turn the clevis on bolt E, as a pivot, to one side, when the hook may be turned and adjusted 70 up or down, as desired, and when properly adjusted the clevis may be turned back into line with the beam and the bolt F be reapplied. It will be noticed that the draft-hook cannot be lost unless the supplemental plate 75 be removed, nor even then unless the said hook should be adjusted immediately under such supplemental plate. While the part G, for convenience of reference, is termed a "draft-hook," it is manifest that it is not of 80 necessity provided with a hook proper, but might be otherwise suitably constructed to facilitate the connection of the team or other motive power.

Having thus described my invention, what I 85 claim as new is—

1. A clevis comprising a main section formed with a base-plate and an arm or front bar extended perpendicularly from the forward end of said base-plate and having its 90 free end threaded, and the supplemental plate having an opening fitted to receive the end of said arm, substantially as set forth.

2. The improved clevis herein described, consisting of the section A, having plate C 95 and arm D, extended at right angle from the forward end of plate C, and having an eccentric wing, d, and notches d' therein, and having its point 1 threaded, the plate B, having an opening to receive the point 1, and the necessary retaining-bolts, substantially as set forth. 100

3. A clevis, substantially as described; com-

prising a main section formed with a base-plate and an arm, connected rigidly with such plate at one end thereof and adapted for engagement by the draft-hook, and the supplemental plate having an opening for the free end of the arm, substantially as set forth.

4. The clevis herein described, comprising the section C, having arm D, formed with a ring, d, having notches d', and with threaded

point 1, the draft-hook G, having opening g, 10 formed with extension g', the plate B, having opening 6 for point 1, and the bolts E and F, substantially as set forth.

GEORGE W. VINSON.
